UNITED STATES PATENT OFFICE.

JACOB L. STAUFENBIEL, OF ST. LOUIS, MISSOURI.

INVALID BED.

Application filed March 24, 1927. Serial No. 177,995.

The present invention has relation to improvements in invalid beds and consists in the novel features of construction more fully set forth in the specification and pointed out in the claim.

Briefly the invention consists in a bed supporting frame embodying a bottom-rest, a back-rest, and individual leg-rests, the back-rest and leg-rests being separately adjustable to effect frequent changes in the position of the patient. Each of these parts is operated by a mechanism handy to the patient himself, so that he may alter the position of these parts should he have sufficient strength for doing so.

The principal object of the invention, aside from providing bed sections separately adjustable, is to so arrange the parts that patients who are not helpless may themselves alter the position of the respective bed sections so that they would not need the constant attendance of a nurse. A further object is to provide independent supporting sections for the body, such as canvas sheets stretched over the frames, or, if desired, individual springs and mattresses; a further object is to construct a bed of this type which would be comparatively simple, durable, and positive in the operation of its respective parts. Further and other advantages will be better apparent from a detailed description of the invention in connection with the accompanying drawings, in which:

Figure 1 is a top plan of my improved invalid bed with parts broken away; Fig. 2 is a side elevation thereof; Fig. 3 is a vertical cross-section taken on the line 3,3 of Fig. 2; Fig. 4 is a vertical cross-section taken on the line 4,4 of Fig. 1; Fig. 5 is an enlarged detail of the operating mechanism for adjusting the respective parts of the bed; Fig. 6 is a vertical longitudinal section taken on the line 6,6 of Fig. 5; and Fig. 7 is a vertical cross-section taken on the line 7,7 of Fig. 1.

Referring to the drawings, F represents a frame composed of side members 1, 1' and end members 2, 2', there being cross-members 3, 3' disposed in spaced relation at an intermediate position on the frame, each of said cross members being secured to the side members 1, 1'. A back-rest 4 is secured to the cross member 3 by hinges 5, 5, said back-rest comprising a frame 6 to which hinges 5, 5 are secured, the side members 7, 7 of said

frame 6 having rods 8, 8 mounted on them, said rods being curved as shown in Fig. 2 for a purpose hereinafter to appear. A canvas supporting sheet 9 is tightly stretched over the frame 6 and is secured at the sides to the rods 8, 8. While I show the sheet 9 secured on the frame by means of cord lacings 9', I do not wish to be restricted thereto as the method of holding the sheet 9 in place is optional with the user of the bed.

Tightly stretched between the cross members 3, 3' and side members 1, 1', is a canvas supporting sheet 10, said sheet being secured in place in like manner as the sheet 9, and having a centrally disposed opening O, the margin of said opening being formed by fixing the canvas in some suitable manner to a wire ring 11. The purpose of the opening O is to simplify the duties in connection with the demands of nature made upon the patient, as it is merely necessary to place a suitable receptacle beneath the opening O, thus avoiding the use of a bed pan. A pair of leg-rest frames 12, 12' are disposed at the front end of the frame F between members 1, 1', end member 2' and cross member 3', said frames being independent of one another and both mounted for oscillation on a rod r extending between said members 1, 1' adjacent to the member 3'. Each of the frames 12, 12' has a canvas sheet 13 tightly stretched over it, the sheets 13 being secured by cord lacing 14 as shown. The sheet 10 together with its supporting members constitutes the bottom-rest and is immovably fixed in place, and the leg-frames 12, 12' together with their supporting sheets 13 constitute leg-rests and are adjustable as is the back-rest comprising the frame 6 and the sheet 9, the mechanism for effecting the adjustment of these parts being as follows:

A short vertical main shaft 15 is mounted in a bearing 16 secured to the side rail 1, said shaft carrying a bevel gear 17 on its lower end and an operating wheel 18 fixed on its upper end. A collar 19 holds the shaft in place in the bearing 16. A shaft 20 is mounted in bearings 21, 21 secured to the under side of side member 1, said shaft 20 having a pinion 22 slidably mounted on its inner end by means of a feather 23. The pinion 22 is movable into and out of engagement with the bevel gear 17 by means of a shift lever 24 pivotally mounted on the side

member 1 and having a pin p in its extremity 25 for engaging slot 26 formed in the hub 22' of the gear 22. The outer end of the shaft 20 has a worm 27 mounted on it for engagement with a worm wheel 28 carried on the adjacent end of counter shaft 29, on the opposite end of which is a drum 30 on which is adapted to be wound a cable 31. The cable 31 has one end connected to the bracket 32 projecting downwardly from the outer end of leg-rest frame 12. A counter-shaft 33 is mounted in bearings 34, 34 secured to the cross member 3, the end of shaft 33 adjacent the actuating gear 17 having a pinion 35 slidably mounted on it by means of a feather 36, said pinion being movable to and from the gear 17 by means of a shift lever 37 (in like manner as pinion 22). The other end of shaft 33 has a bevel gear 38 fixed to it which meshes with a bevel gear 39 fixed to the end of a shaft 40 mounted in bearings 41, 41 beneath the side member 1'. A shaft 42 is mounted in suitable bearings beneath the foot-end member 2' of supporting frame F and is connected to shaft 40 by means of a worm 43 fixed to the end of shaft 40 and a worm wheel 43' on the adjacent end of shaft 42, the opposite end of said shaft having a drum 44 fixed to it on which a cord 45 is adapted to be wound. One end of the cord 45 is connected to a bracket 46 projecting downwardly from the end of leg-rest frame 12'. Thus, it will be seen that on rotating the driving gear 17, either shaft 20 may be rotated to cause the cord 31 to wind onto or off drum 30, or shaft 33 and shaft 40 may be rotated to cause cord 45 to wind on or off of drum 44 depending on whether pinion 22 or pinion 35 is in mesh with the driving gear 17. Of course, as the cords are unwound from the drums 30 and 44, the leg-rests will be lowered, and as the cords are wound onto the drums, the leg-rests will be raised, or either leg-rest may be raised or lowered as desired.

A bar 47 is secured to the side members 7 of frame 6 and has a pair of lugs 48 fixed to it in spaced relation, to each of which is pivotally connected a rack bar 49 adapted to mesh with a cogwheel 50 fixed on counter-shaft 51 extending transversely of the frame F and rotatable in suitable bearings 52, 52 mounted on the under side of

members 1, 1'. One end of shaft 51 has a worm wheel 53 fixed on it adapted to mesh with a worm 54 fixed onto the end of shaft 55, mounted in bearings 56, 56 beneath member 1, the opposite end of shaft 55 having a pinion 57 slidably mounted on it by means of a feather 57', said pinion being adapted to be moved into and out of engagement with driving gear 17 by means of a shift lever 58, similar to shift lever 24. A stirrup 60 is mounted on shaft 51 and confines the rack bar 49 to its path of travel so that it will be held in mesh with the teeth of cogwheel 50. From what has just been said, it is apparent that if the gear 17 is rotated while the pinion 57 is in mesh with said gear, shafts 55 and 51 will be rotated as well as the cogwheel 50, and the rack bars 49 will be moved either upwardly or downwardly to raise or lower the back-rest comprising the frame 6 together with its covering sheet 9. Thus, either the back-rest and the leg-rests may be adjusted, or any one of these members may be adjusted to meet the demands of the patient occupying the bed, all of which is done by the operator in one position; that is, in the immediate vicinity of the operating wheel 18 whereby the driving gear is actuated.

The sheet 9 will follow the curvature of the rods 8, 8 between which it is stretched, and since these members are curved to correspond with the natural curvature of a person's back, the sheet will also follow this curvature increasing the comfort of the back-rest.

Having described my invention, I claim:

An invalid bed comprising a supporting frame, a bottom-rest fixed to said frame, a back-rest hingedly mounted on the frame adjacent to the rear edge of the bottom-rest, a pair of independent leg-rests hingedly mounted on the frame adjacent to the front end of said bottom-rest, and means for adjusting the back-rest and leg-rests, said means comprising a single actuating device and clutches for connecting any desired selection of said rests to the actuating device.

In testimony whereof I hereunto affix my signature.

JACOB L. STAUFENBIEL.
